**PROCESS FOR REDUCING OBJECTIONABLE ODOR
OF PHOSPHORODITHIOATE COMPOUNDS**

Simon Frank, Stamford, and George N. Gagliardi, Springdale, Conn., assignors to American Cyanamid Company, New York, N.Y., a corporation of Maine

No Drawing. Filed June 16, 1959, Ser. No. 820,591

7 Claims. (Cl. 260—461)

This invention relates to a process for reducing the objectionable odor of a malodorous phosphorodithioate compound. More particularly, it relates to a process for the removal of odor from a malodorous phosphorodithioate insecticide derived from dithiophosphoric acid.

Phosphorodithioate insecticides of the type with which the present invention is concerned are usually esters and may be represented by the general formula

in which R_1 and R_2 are each selected from the group consisting of aliphatic and aromatic hydrocarbon radicals, and R_3 and R_4 are selected from the group consisting of hydrogen, aliphatic and aromatic hydrocarbon radicals. Such esters are well known and may be conveniently prepared by reacting an acid phosphate of the formula

in which R_1 and R_2 have the meaning shown above, with an unsaturated compound of the formula

in which R_3 and R_4 have the meaning shown above as described in United States Letters Patent No. 2,578,652. A typical ester is O,O-dimethyl-S-(1,2-dicarboxyethyl)-phosphorodithioate which is commercially available as malathion insecticide.

Phosphorodithioate insecticides of the type hereinbefore described have achieved a recognized place in the art as extremely useful insecticides by virtue of the fact of their relatively low mammalian toxicity. Such phosphorodithioate insecticides find use for the control of aphids, spider mites, scales, house flies as well as a wide range of other sucking and chewing insects. However, more widespread use of such phosphorodithioate insecticides has been hampered to a large extent because such insecticides possess an odor which is objectionable. Of course, numerous expedients have been proposed in an attempt to reduce the obnoxious odor of such compounds. Such commonly employed methods, some of which include the use of various oxidizing substances, however, have been found to be difficult, costly and time consuming since they usually require several steps among

2

which are distillation and phase separation, filtration, drying, and the like. Furthermore, such methods have not proved to be wholly satisfactory. Thus, for example, it has been noted that a phosphorodithioate insecticide which has been refined by a steam distillation procedure develops a strong obnoxious odor after storage for several months. To the present, there is lacking a simple, inexpensive and expeditious process for removing the objectionable odor found in phosphorodithioate insecticides.

It has now been discovered that the objectionable odor which is characteristic of phosphorodithioate compounds, especially phosphorodithioate insecticides, can be effectively and remarkably reduced by the simple expedient of subjecting such a compound to the action of ozone. Surprisingly, it has been found that merely by passing an ozone containing gas through or in contact with such a phosphorodithioate insecticide, an insecticide having a pleasant ester-like odor is produced. Such an insecticide, substantially devoid of malodor, is in contrast to both the crude or technical grade of insecticide and a refined grade of phosphorodithioate insecticide. Such an insecticide may be advantageously employed, for example, in fly sprays and in suitable solvents for the impregnation of textiles, particularly articles of clothing, to provide insecticidal activity. It may be used with advantage for the control of numerous household and garden pests. Further, the treatment renders the insecticide for even wider use, as, for example, in grain storage elevators and the like. The insecticide after having been subjected to the treatment with ozone is substantially free from malodor and acceptable for use by the householder, gardener and others who have disapproved of the heretofore available insecticide because of its objectionable odor. However, none of the active properties applicable for the destruction of insects have been lost by the treatment. The treatment of the present invention further improves the insecticide in that even after prolonged storage under various conditions little or no objectionable odor is noted in the so-treated insecticide.

The present process, therefore, involves the passing of ozone, or an ozone containing gas, through or in contact with the insecticide so as to reduce the objectionable odor of a malodorous phosphorodithioate insecticide. It has been found that the ozone used in the present process may be admixed with oxygen, air or other non-reactive diluent gases without affecting the efficiency of the process. Generally, an ozone concentration of from about 0.05 to about 3.5 weight percent in these gases is effective. It has been found that as little as 0.1 weight percent of ozone based upon the weight of insecticide may be used in the process though higher concentrations are generally employed. However, amounts ranging up to about 3.5 weight percent or above are also effective, but the use of a larger amount is not especially desirable from a cost standpoint and is also not usually required to produce the desired level of odor control. Conventional and well-known gas liquid contact apparatus, among which may be mentioned the packed column type, may be used for the treatment of the insecticide with ozone since the apparatus employed is not the essential feature of this invention. Further, even

the bubbling of ozone through the insecticide contained in a suitable vessel is effective. Following the passage of ozone through or in contact with said insecticide, an inert and non-reactive gas such as air, oxygen, nitrogen or the like may be used to sweep out volatiles, such as residual ozone and the oxidation products produced during the treatment, which have been expelled from the malodorous insecticide. The process may be carried out over a considerably wide temperature range. When the insecticide to be deodorized is a liquid, temperatures from about 25° C. to about 90° C. may be effectively employed. Furthermore, while a liquid phosphorodithioate insecticide may be treated with ozone or an ozone containing gas in the absence of solvent at these process temperatures, it is also possible to effect a reduction of objectionable odor when a solvent for the insecticide is employed. Among the large number of solvents suitable for the phosphorodithioate insecticides may be mentioned esters, alcohols, ketones, hydrocarbons, and other suitable solvents which are non-reactive with the insecticides and with ozone.

In order to facilitate a better understanding of the invention, the following examples are given primarily for the purpose of illustrating certain more specific details thereof. Unless otherwise stated, all parts are by weight.

EXAMPLE I

In a continuously stirred pot reactor are placed 100 parts of technical grade, liquid O,O-dimethyl-S-(1,2-dicarbethoxyethyl)-phosphorodithioate, having a considerable amount of malodor. An ozone air mixture is then bubbled through the insecticide maintained at about 85° C. for a period of forty minutes until a quantity of ozone equal to approximately 0.5 percent by weight of the charge of O,O-dimethyl-S-(1,2-dicarbethoxyethyl)-phosphorodithioate has been passed therethrough. Air is then swept through the system to expel volatiles such as sulphur dioxide which may be present and residual ozone. The treated insecticide is found to possess a fragrant, pleasant odor in contrast to the normally malodorous insecticide.

EXAMPLE II

In a continuously stirred pot reactor are charged 100 parts of technical grade liquid O,O-dimethyl-S-(1,2-dicarbethoxyethyl)-phosphorodithioate, having some malodor. An ozone-oxygen mixture, in which the amount of ozone present is about 2 weight percent, is then admitted below the surface of the liquid, maintained at 85° C., for a period of approximately fifty minutes, until a quantity of ozone equal to approximately 0.6 percent by weight of the charge of O,O-dimethyl-S-(dicarbethoxyethyl)-phosphorodithioate has been passed therethrough. Subsequently, air is swept through the system to remove the volatiles from the treated material. The treated insecticide is found to be substantially free of the normally objectionable and obnoxious odor customarily found with the insecticide.

It will be obvious to those skilled in the art that there may be many minor method variations and that different kinds of equipment may be used in order to reduce the objectionable odor of malodorous phosphorodithioate compounds. However, in order to illustrate even further a manner in which the reduction of objectionable odor may be accomplished there is summarized in the table below operating conditions employed in additional examples in which a malodorous phosphorodithioate compound is contacted with an ozone containing gas in a conventional gas-liquid contact device, a stainless steel column packed with three-eighths inch (3/8") Raschig rings. O,O-dimethyl-S-(1,2-dicarbethoxyethyl)-phosphorodithioate commonly known as malathion insecticide is treated in each of the following examples.

4
Table

Example.....	III	IV	V
Column diameter, in.....	3	3	3
Column height, ft.....	6	4	4
Malathion feed rate, lb./hr.....	22.5	22.5	15
Air rate, c.f.m.....	2.6	2.6	2.9

Odor characteristics of treated malathion.....	(1)	(1)	(1)

¹ Fragrant, inoffensive.

While the deodorization of O,O-dimethyl-S-(1,2-dicarbethoxyethyl)-phosphorodithioate is principally exemplified in the foregoing description, it is to be understood that any such dithiophosphate ester, for example, O,O-dimethyl-S-(1,2-dicarbomethoxyethyl)-phosphorodithioate, O,O-dimethyl-S-(1,2-dicarbo-n-propoxyethyl)-phosphorodithioate, O,O-dimethyl-S-(1,2-dicarbisopropoxyethyl)-phosphorodithioate, O,O-diethyl-S-(1,2-dicarbomethoxyethyl)-phosphorodithioate, O,O-diethyl-S-(1,2-dicarbethoxyethyl)-phosphorodithioate, O,O-diethyl-S-(1,2-dicarbo-n-propoxyethyl)-phosphorodithioate, O,O-diethyl-S-(1,2-dicarbisopropoxyethyl)-phosphorodithioate, and others disclosed in United States Patent No. 2,578,652, may advantageously be treated by the process of the present invention.

We claim:

1. A process for reducing the objectionable odor of a malodorous phosphorodithioate compound which comprises subjecting said compound to the action of ozone in an amount from about 0.1 percent to about 3.5 percent by weight of said compound.

2. A process for reducing the objectionable odor of a malodorous phosphorodithioate compound which comprises subjecting said compound to the action of a non-reactive gas containing ozone, the amount of ozone being from about 0.1 percent to about 3.5 percent by weight of said compound.

3. A process for reducing the objectionable odor of a malodorous phosphorodithioate compound represented by the formula

50 in which R₁ and R₂ are each selected from the group consisting of aliphatic and aromatic hydrocarbon radicals and R₃ and R₄ are each selected from the group consisting of hydrogen, aliphatic and aromatic hydrocarbon radicals which comprises subjecting said compound to the action of ozone in an amount from about 0.1 percent to about 3.5 percent by weight of said compound.

4. A process as in claim 3 in which said compound is O,O-dimethyl-S-(1,2-dicarbethoxyethyl)-phosphorodithioate.

5. A process for reducing the objectionable odor of a malodorous phosphorodithioate compound represented by the formula

65 in which R₁ and R₂ are each selected from the group consisting of aliphatic and aromatic hydrocarbon radicals and R₃ and R₄ are each selected from the group consisting of hydrogen, aliphatic and aromatic hydrocarbon radicals which comprises dissolving said compound in a suitable solvent therefor and passing ozone in an amount from about 0.1 percent to about 3.5 percent by weight of said compound in contact with said compound.

70 6. A process for reducing the objectionable odor of

a malodorous phosphorodithioate compound represented by the formula

in which R_1 , R_2 , R_3 and R_4 are each selected from the group consisting of aliphatic and aromatic hydrocarbons which comprises subjecting said compound to the action of ozone in an amount from about 0.1 percent to about 3.5 percent by weight of said compound and subsequently passing an inert gas through the so-treated compound to expel volatiles therefrom.

7. A process as in claim 6 in which said compound is O,O - dimethyl - S - (1,2 - dicarbethoxyethyl) - phosphorodithioate.
